UNITED STATES PATENT OFFICE

EMMETT L. JOHNSTON AND ROBERT LLOYD GREEN, OF ROANOKE, VIRGINIA

COMBINATION TOOL

Application filed June 20, 1928. Serial No. 286,877.

The present invention relates to improvements in measuring instruments and has reference more particularly to a combination tool for use by brick layers and other mechanics.

One of the important objects of the present invention is to provide a compound tool, which includes a square, rule, plumb and level.

10 A further object is to provide a combination tool that is compact, the parts being so arranged as to permit any one of the aforementioned instruments to be used whenever desired.

15 A further object is to provide a combination tool which includes a means for securing the swinging arm in a folded position within a longitudinal recess provided therefor in the stock.

20 A further object includes the provision of end wear plates.

Still a further object is to provide a combination tool of the above mentioned character which is simple in construction, inexpensive, strong and durable, and further well adapted to the purpose for which it is designed.

Other objects of the invention will become apparent as the nature of the invention proceeds and when taken in connection with the accompanying drawings.

In the accompanying drawings, forming a part of this application and in which like numerals designate like parts throughout the several views:

Figure 1 is a side elevation of the combination tool embodying my invention, showing the vertically swinging arms in a folded position.

40 Figure 2 is a top plan view.

Figure 3 is a sectional view through one end of the stock, showing the recess formed in the upper edge of the stock for housing the vertically swinging arm, the latter being shown in a raised position.

Figure 4 is a detail showing the pivotal support for the vertically swinging arm, and

50 Figure 5 is a sectional view, taken approximately on the line 5—5 of Figure 1, looking in the direction of the arrows.

In the drawings, wherein for the purpose of illustration is shown the preferred embodiment of my invention, the numeral 1 designates a substantially rectangular shaped stock that is preferably constructed of wood and as is clearly shown in Figure 5, the opposite side faces of the stocks are cut out along their longitudinal edges to receive the metallic strips 2, any appropriate securing means being driven through these strips into the stock 1 as shown at 3, and it will be observed that the outer faces of these strips lie flush with the respective side faces of the wooden stock 1. Certain of these metallic strips provide a means whereby the tool may be used as a rule, and to this end graduations are arranged on the outer face of such strips as indicated at 4, in Figure 1.

Metallic wear plates 5 and 6 are secured on the ends of the stock 1 and one side edge of the wear plate 6 is formed with the graduations 7, as also clearly shown in Figure 1.

The top of this wooden stock 1 is formed with the longitudinally extending recess or cavity 8, at one end thereof, and the upper edge of the wear plate 6 is formed with a slot 9 that communicates with the outer end of the recess 8. The inner end of this recess 8 is bevelled as indicated at 10, and furthermore a notch 11 is arranged at the top of the bevelled end 10 in which a nail or the like may be inserted for swinging the arm 12 upwardly.

This arm has its outer end disposed within the slot 9 formed in the plate 6 and the pivotal connection for the outer end of this arm comprises a screw 13 that is threaded in a transverse opening provided therefor in one side of the plate 6, the outer end of the opening being enlarged to accommodate the head of the screw, so that the head of the screw will not project beyond the face of the plate 6.

A reduced unthreaded pin 14 is formed on the inner end of the screw and this pin extends through an opening provided therefor in the outer end of the arm 12 and is disposed within a suitable socket 15 formed in the plate 6 on the opposite side of the slot 9 in which the threaded recess for receiving the screw 13 is formed and this detail is more clearly illustrated in Figure 4.

100

The upper edge of the outer end portion of the arm is cut away to form a shoulder 16 that engages with the upper face of the plate 6 when the arm 12 is swung upwardly to a vertical position so that further swinging movement of said arm 12 will be prevented. The arm is provided with the graduations 17 on either or both sides thereof, whereby the same may be used also as a rule, and when the arm is disposed in the position shown in Figure 3, said arm will cooperate with the stop to provide a square.

The inner end of the vertically swinging arm 12 is notched as illustrated at 18, to facilitate gripping the same, and for the purpose of holding the swinging arm in a folded position for maintaining the same within the recess 8, there is provided with spring pressed latch 19 arranged in one side of the stock 1, the rounded inner end of the latch extending into the recess and adapted to engage with the detent 20 formed in the adjacent side of the inner end portion of the arm 12 as clearly indicated in Figure 5.

The spring latch may be forcibly disengaged from the detent when the inner end of the arm 12 is grasped and pulled outwardly of the recess 8, whenever it is desired to use the arm.

The stock 1 is formed in its central portion with the through slot 21, in which is arranged a spirit level 22, as shown very clearly in Figures 1 and 3 of the drawings. Furthermore, the stock 1 has arranged inwardly of its ends the plumb beads 23, and the lower edge of the vertically swinging arm 12 is cut out, as at 24, so as not to interfere with the adjacent plumb bead 23 and to permit the upper edge of the arm 12 to lie flush with the upper face of the stock 1, when said arm is in a folded position and disposed in the recess 8.

The stock is furthermore formed in its side faces with the longitudinally extending finger engaging grooves 26 and this detail is shown in Figure 1. The other end of the rule carrying stock is formed with a through hole shown at 25 in Figure 1.

For the purpose of maintaining the swinging arm 12 in any vertically adjusted position there is provided a spring strip 30 that is secured at its forward end in a suitable recess 31 formed in the top of the wooden stock 1 as shown in Figure 2. The free end of this spring strip bears against the pivoted end of the swinging arm 12 and is furthermore formed with an opening to accommodate the reduced pin 14 formed on the inner end of the screw 13. By tightening the screw 13, the arm 12 will be positively secured in any vertically adjusted position.

The use of my improved combination tool will be readily appreciated by those skilled in the art, and therefore a detailed description of the various uses of the instrument is believed unnecessary.

While I have shown the preferred embodiment of my invention, it is to be understood that various changes in the size, shape and arrangement of parts may be resorted to, without departing from the spirit of the invention or the scope of the appended claim.

What I claim as new is:

A tool comprising an elongated stock of rectangular cross-section and having a longitudinally extending recess opening outwardly of one end thereof, a wear plate at the slotted end of the stock and having its upper portion provided with a slot communicating with the open outer end of the recess and having a transverse opening in one side thereof communicating with the said slot, fastening screws attaching the plate to the stock, a pivot screw threadedly engaged in the said transverse opening of the plate and having a reduced unthreaded pin on its inner end, and an arm pivotally supported on said pin and normally housed in the recess of the said stock, said arm, wear plate and stock having graduations on a corresponding side reading from a common zero.

EMMETT L. JOHNSTON.
ROBERT LLOYD GREEN.
